(57) **CLAIM**

The ornamental design for a charging station for robot, as shown and described.

DESCRIPTION

FIG. 1 is a front view of a charging station for robot, showing our new design;

FIG. 2 is a top view thereof;

FIG. 3 is a back view thereof;

FIG. 4 is a bottom view thereof; and,

FIG. 5 is a front perspective view thereof.

The broken lines shown in the drawings illustrate portions of the charging station for robot that form no part of the claimed design.

1 Claim, 5 Drawing Sheets
